Patented May 30, 1922.

Inventor:

Sidney M. Israel,
By his Attorney, Leo F. Kiath

UNITED STATES PATENT OFFICE.

SIDNEY M. ISRAEL, OF RICHMOND HILL, NEW YORK.

DESIGN FOR A COMBINED LAMP STAND AND SMOKING SET.

61,018.

Specification for Design.

Patented May 30, 1922.

Application filed April 14, 1921. Serial No. 461,420. Term of patent 3½ years.

To all whom it may concern:

Be it known that I, SIDNEY M. ISRAEL, a citizen of the United States, residing at Richmond Hill, county of Queens, and State of New York, have invented a new, original, and ornamental Design for a Combined Lamp Stand and Smoking Set, of which the following is a specification, reference being had to the accompanying drawing, forming part thereof.

The figure is a perspective view of a combined lamp stand and smoking set, showing my new design.

I claim:

The ornamental design for a combined lamp stand and smoking set, as shown.

SIDNEY M. ISRAEL.
